CLAIM

The ornamental design for a firearm sight, as shown and described.

DESCRIPTION

FIG. 1 is a rear perspective view of a firearm sight showing my new design;

FIG. 2 is a side elevational view of FIG. 1;

FIG. 3 is a top plan view of FIG. 1;

FIG. 4 is a bottom view of FIG. 1;

FIG. 5 is a rear view of FIG. 1;

FIG. 6 is a front view of FIG. 1;

FIG. 7 is a rear perspective view of another embodiment of a practical sight showing my new design;

FIG. 8 is a rear view of FIG. 7;

FIG. 9 is a rear perspective view of yet another embodiment of a practical sight showing my new design;

FIG. 10 is a rear view of FIG. 9;

FIG. 11 is a rear perspective view of still another embodiment of a practical sight showing my new design; and,

FIG. 12 is a rear view of FIG. 11.

The rear views of FIGS. 7, 9, and 11, represent the second through fourth embodiments of the design with all other views being the same as that shown in the first embodiment, FIGS. 1-6.

Portions of the firearm sight shown in broken lines form no part of the claimed design.

My practical sight is characterized by a gradually sloping rear surface, and a radiused front surface as viewed from the side.
